UNITED STATES PATENT OFFICE.

MARK G. RAY, OF ATLANTA, GEORGIA.

DESIGN FOR A SHADE FOR LAMPS.

45,727.

Specification for Design.

Patented May 5, 1914.

Application filed February 17, 1914. Serial No. 819,288. Term of patent 7 years.

To all whom it may concern:

Be it known that I, MARK G. RAY, a citizen of the United States of America, residing at Atlanta, in the county of Fulton and State of Georgia, have invented a new, original, and ornamental Design for a Shade for Lamps, of which the following is a specification, reference being had to the accompanying drawing, forming part thereof.

In the drawings, Figure 1 is a perspective

view of a shade, showing my design. Fig. 2 is a plan view.

I claim:

The ornamental design for a shade for lamps, as shown.

MARK G. RAY. [L. S.]
